(57) **CLAIM**

The ornamental design for an illumination device, as shown and described.

DESCRIPTION

FIG. 1 is a rear isometric view of a first embodiment of an illumination device showing our new design;

FIG. 2 is a rear view thereof;

FIG. 3 is a front view thereof;

FIG. 4 is a left side view thereof;

FIG. 5 is a right side view thereof;

FIG. 6 is a top view thereof;

FIG. 7 is a bottom view thereof;

FIG. 8 is a rear isometric view of a second embodiment of an illumination device showing our new design;

FIG. 9 is a rear view thereof;

FIG. 10 is a front view thereof;

FIG. 11 is a left side view thereof;

FIG. 12 is a right side view thereof;

FIG. 13 is a top view thereof;

FIG. 14 is a bottom view thereof;

FIG. 15 is a rear isometric view of the second embodiment with the lighting modules shown removed for clarity of illustration;

FIG. 16 is a rear view thereof;

FIG. 17 is a front view thereof;

FIG. 18 is a left side view thereof;

FIG. 19 is a right side view thereof;

FIG. 20 is a top view thereof; and,

FIG. 21 is a bottom plan view thereof.

The broken-line disclosure in first embodiment represents portions of the illumination device which form no part of the claimed design.
